UNITED STATES PATENT OFFICE

HERBERT B. NEWTON, OF BROOKLINE, MASSACHUSETTS

WHEELBARROW

Application filed January 21, 1928. Serial No. 243,335.

This invention is embodied in a one-wheeled wheelbarrow, the bucket or load receptacle of which is entirely enclosed by the wheel at one side of, and below the axis thereof, and suspended so that the entire weight of the bucket and its load is supported by the wheel, the wheel being formed as a cage, permitting the loading and unloading of the bucket, the chief object being to permit the transportation of the load with no muscular effort other than that required to propel the barrow.

Other objects will hereinafter appear.

Of the accompanying drawings forming a part of this specification,—

Figure 1 is a side elevation of a wheelbarrow embodying the invention.

Figure 2 is a top plan view of the same.

Figure 3 is a perspective view of the crank or drop axle element, shown by Figures 1 and 2.

Figure 4 is a fragmentary section on line 4—4 of Figure 1.

The same reference characters indicate the same parts in all of the figures.

The bucket or load receptacle of my improved wheelbarrow includes, in this instance, a curved bottom 12, and sides 13, 13, the ends of the bottom and the upper edges 39 of the sides forming the mouth of the bucket.

Fixed to the bucket and projecting from opposite sides of the mouth portion thereof, are alined axle arms 14, 14, the relative arrangement of the bucket and arms being such that the center of gravity of the bucket is at one side of the axial line of said arms.

The axle arms may be rigidly secured to the bucket by any suitable means. Said arms are preferably the end members of a crank or drop axle, formed as shown by Figure 3, and including rods 15, joined to the arms 14, at an angle therewith, and bearing on the sides of the bucket, and a neck 16 joined to, and connecting the rods and extending across the bottom of the bucket, the arms and neck constituting a sling supporting the bucket.

The neck 16 is preferably relatively wide, as shown by Figure 3, so that it has an extended bearing on the bucket bottom, the neck being secured to the bottom by bolts or

rivets 17. The sides 13 of the bucket may be provided with lugs 18, bearing on opposite sides of the rods 15.

The wheel is enlarged and formed to permit the enclosure of the bucket within it, with the center of gravity of the bucket below the axis of the wheel. The circular rim of the wheel may be composed of two annular members 19, angular in cross section, and abutted together, as best shown by Figure 4. The wheel includes two spaced apart hubs 20, mounted to rotate on the axle arms 14, and spokes 21, riveted or otherwise fixed at their inner ends to the hubs, and at their outer ends to the rim, the sections 19 of the rim being preferably secured to each other by bolts or rivets 22 (Figure 4), which also secure the outer ends of the spokes to the rim. The spokes 21 are bent as indicated by Figure 1, to form side members of the cage-shaped wheel, the spokes being out of contact with the bucket and the rim in a plane midway between the hubs. The axle arms are adapted to be turned freely by the weight of the bucket in the bearings provided by the hubs, to automatically locate the center of gravity of the bucket and its load directly under the axial line of the arms, so that the load is supported entirely by the wheel.

The barrow includes propelling means engaged with the axle arms 14, whereby the operator may push or pull. I prefer to embody said means in two handle-bars 24, having bearings at their inner ends in which the axle arms are journaled, the bars being adapted to swing in vertical planes, so that their outer ends may be elevated, as shown by Figure 1, and depressed to bear on the ground, and a cross-bar 25, connecting the outer end portions of the arms. The propelling means is free from positive connection with the bucket, so that the propulsion of the barrow by said means cannot change the location in which the center of gravity of the bucket and its load is automatically maintained, the propelling means being independent of the bucket.

A brake-shoe 26, carried by the propelling means, is adapted to be pressed by the operator against the periphery or tread of the

wheel rim and retard the rotation of the wheel. Said shoe is preferably formed on one end of a lever 27, fulcrumed on the cross-bar 25. The spokes are sufficiently spaced 5 apart to permit the load to be inserted in the bucket and dumped therefrom between adjacent spokes.

To permit the dumping of the load by a partial rotation of the wheel, I provide the 10 bucket with a coupling member engageable with a member of the wheel, to cause the bucket to turn with the wheel. Said member is preferably a slide 28, movable in a guide 29, fixed to a side of the bucket, and provided with a hook 30, adapted to engage a spoke 21, when the slide is moved to the dotted line 15 position shown by Figure 2.

The handle-bars 24, rigidly connected by the cross-bar 25, maintain the barrow with 20 the wheel upright, when the outer ends of the handles bear on a supporting surface. The handle-bars may have downwardly projecting leg portions 24a.

As implied by the foregoing description 25 and the following claims, I am not limited to the specific construction shown by the drawings, except as otherwise required by certain of the more limited claims.

I claim:

30 1. A wheelbarrow comprising a bucket, aligned axle arms fixed to the bucket and projecting from opposite sides of the mouth portion thereof, so that the center of gravity of the bucket is at one side of the axial line of said arms, a wheel having spaced apart hubs mounted to rotate on the axle arms, the wheel being formed as an open cage enclosing the bucket, and adapted to permit the loading and unloading thereof, propelling means engaged with the axle arms, the arrangement being such that the bucket is supported wholly by the wheel, with its center of gravity below the axial line of the axle arms, and a coupling member carried by the bucket and 35 engageable with a member of the wheel, to cause a dumping movement of the bucket when the wheel is turned.

2. A wheelbarrow comprising a bucket, aligned axle arms fixed to the bucket and projecting from opposite sides of the mouth portion thereof, so that the center of gravity of the bucket is at one side of the axial line of said arms, a wheel having spaced apart hubs mounted to rotate on the axle arms, the wheel being formed as an open cage enclosing the bucket, and adapted to permit the loading and unloading thereof, propelling means engaged with the axle arms, the arrangement being such that the bucket is supported wholly by the wheel, with its center of gravity below the axial line of the axle arms, and a hooked slide movable in a guide on the bucket and engageable with a spoke of the wheel, to cause a dumping movement of the 45 bucket when the wheel is turned.

3. A one-wheeled wheelbarrow comprising, in combination, a bucket having aligned axle arms fixed to and projecting from opposite sides of the mouth portion thereof, the center of gravity of the bucket being wholly at one side of said arms, a wheel formed as a bucket-containing cage and composed of spaced apart hubs mounted to rotate on the axle arms, a rim concentric with the hubs, and two series of spokes connecting the rim with the hubs and maintaining the rim in a plane midway between the hubs, the bucket being maintained by gravity below the axle arms and hubs when the wheel stands in a vertical plane on a supporting base, so that the bucket mouth automatically faces upward, the spokes being spaced apart to permit the insertion and discharge of a bucket load therebetween, and spaced apart rigidly connected push bars mounted to swing on the axle arms and adapted to be manipulated by the operator to propel the barrow, and depressed to bear on a supporting base, and maintain the wheel in a vertical plane and the bucket mouth facing upward when the barrow is at rest.

In testimony whereof I have affixed my signature.

HERBERT B. NEWTON.
